INCENDIARY BOMB

Speers G. Ponder and Harry M. Brandt, United States Army, assignors to the United States of America as represented by the Secretary of War

Application February 8, 1945, Serial No. 576,868

2 Claims. (CL 102-6)

(Granted under Title 35, U. S. Code (1952), sec. 266.)

1

The invention described herein may be manufactured and used by or for the Government for governmental purposes without the payment to us of any royalty thereon.

This invention relates particularly to a tail ejection type bomb designed to have a high terminal velocity suitable for precision bombing from high altitudes and for penetration into resisting structures. It relates more particularly to tail ejection bombs having an efficient capacity for incendiary fillings.

Since the beginning of the present war, much effort has been devoted to developing tail ejection bombs intended to function after penetrating a target to forcefully eject a large mass of incendiary material. To fulfill its functions efficiently, the bomb should have a high filling capacity, a high drop accuracy and reliable ejection action. Certain tail ejection type incendiary bombs meeting these requirements have been designed but have had the disadvantage of being unsuitable for pin point bombing and unsuitable for penetrating resisting roof structures of industrial and storage installations.

The present invention has the object of providing a bomb having ballistics comparable to a 250 lb. general purpose bomb even with a much relatively smaller size unit, e. g. 30 to 45 lbs. favorable for clustering and meeting requirements set forth.

The tail ejection type bomb provided herewith functions efficiently with the aid of the following features: (a) a body with a streamlined form yet with high filling capacity; (b) a nose having piercing ability with avoidance of crushing and disruption of the bomb's firing mechanism; and (c) an extensible tail for flight stabilization designed to accommodate the bomb for efficient clustering in a restricted space. In addition to these several features other cooperating features are involved such as an intervally balanced construction, a construction which facilitates manufacture and assembly, a construction which reduces possibilities of leakage and malfunctioning, and a construction which facilitates handling and loading.

A practical embodiment of the bomb illustrating the described advantageous features will be explained with reference to the accompanying drawing which shows a longitudinal cross-sectional view of the bomb.

Referring to the drawing, the principal parts of the bomb are the body casing 1 for enveloping the bomb filling 2, a nose member 3 preferably formed for structure piercing action and adapted

for holding an anti-personnel explosive charge 4 with part of the firing mechanism; an adaptor member 5 of heavy construction for attaching the nose member 3 to the body casing and for holding other parts of a fuze mechanism and sealing members; and a tail structure 6 to which is attached an extensible tail assembly.

The nose member is advantageously given a thick wall construction and an ogival form for improvement of strength, flight, and piercing action. In its open rear end, the nose member has a threaded portion 7 for engagement with a threaded flange of the adaptor 5. Two small depressions 8 in the nose member 3 are used for insertion of wrench prongs for screwing the nose member into the adaptor 5. An aperture 9 located at the central lower extremity of nose member 3 is provided for receiving a firing pin plunger head 10, which is retained in its outermost position by the shoulder 11 adjoining the aperture 9.

A closed cup-shaped member 12 having a central tubular inside wall 13 closely fits the inside wall of nose member 3 and is useful as a container of a high explosive charge 4, also as a container for a time delay fuse 14. The explosive charge 4 may comprise any suitable high explosive substance, such as, tetryl, TNT, or the like, capable of fragmenting nose member 3 and sending the fragments at high velocity into space. The time delay fuse may be a cord type fuse containing a slow burning black powder composition, such as a conventional Miner's fuse. The time delay fuse is preferably disposed as a compact winding at the upper part of the container 12 with a partition 15 separating the fuse from the explosive charge 4, but with a final burning end 16 projected through a small hole for contact with the explosive charge 4.

The head 10 of the firing pin plunger is attached to firing pin 17 which extends through the passage defined by the tubular closure 13. A coil spring 18 surrounding the firing pin 17 is under compression between head 10 and the base of adaptor 5 for maintaining the firing pin in an outwardly projected position until it is forced to yield on impact of the bomb with the fuze armed.

The adaptor 5 has a lateral bore 19 for receiving a slidable safety pin plunger 20, which when depressed inwardly by pressure of an adjacent bomb in a cluster unarms the fuze in obstructing movement of the firing pin 17 toward a primer 21. A coil spring 22 surrounding the safety pin 20 under compression tends to eject the safety

pin 20 when relieved of pressure on its external head end.

The primer cap 21 is seated in a suitable part of the adaptor plate 5 aligned with the firing pin 17 for ignition thereby. Contiguous to the primer cap 21 is placed a suitable delay powder train 23, such as may contain slow burning composition for obtaining a time delay burning of about 1 to 3 seconds before a first fire charge 24 of black powder is affected. The first fire charge is preferably contained by a plastic cup 25 cemented to the end of the delay train and primer cap holder 26 for separation from an ejection charge 27.

The ejection charge 27 comprises a suitable amount of a propellant powder such as grade A#4 Army glazed black powder for obtaining the desired ejection of the bomb filling. It is preferred that the ejection charge contain an admixture of finely divided pyrophoric material, such as powdered magnesium coated with about 3% linseed oil, or aluminum powder. A suitable ejection charge comprises at least about 4 to 7 g. of the black powder with about equal amount of the powdered magnesium coated with about 3% of the linseed oil.

The ejection charge is housed by the dome or inverted cup-shaped pressed steel member 28 sealed at its rim to the adaptor plate 5. A pressed steel dome 29 likewise sealed to the adaptor plate 5 and spaced from the dome 28 provides therewith a receptacle for containing a charge of white phosphorus 30. A threaded opening 36 in the side of the adaptor 5 affords a convenient means for filling the cavity between dome 25 and the dome 29 with a white phosphorus charge. The threaded opening 36 may be closed after the filling with a suitable threaded plug (not shown).

The casing 1, forming the principal part of the bomb body is advantageously formed of pressed sheet-metal having satisfactory structural strength with thinness to increase the filling capacity, e. g., sheet steel of about 19 gage. For improved ballistics, the casing 1 may be designed to give the bomb a more streamlined shape by widening its cross section near the middle part. For more efficient clustering the casing 1 may be polygonal in cross section rather than circular.

At its tail end of the bomb, the casing 1 is preferably extended into a tapered thinner wall section 6. The section 6 may be an integral part of casing 1 or be sheet metal of thinner wall brazed to the thicker wall casing 1. The thin wall section 6 is fastened and secured to casing 1 to be susceptible to disruption therefrom upon ejection of the incendiary charge 2 when the ejection charge 27 is fired.

At its apex, the conical or pyramidal tail end section 6 is secured to a sealing plug 31 in threaded engagement with adaptor 32. A tubular well 33 is sealed at its upper end to a bottom circular projection 34 of adaptor 32 and extends centrally down into the bomb to a closed bottom 35. A sliding tubular plunger 37 is flared outwardly at its end which slides along the inner surface of well 33 and is projected outwardly from the well by the force of the compressed coil spring 38. The coil spring 38 has ends bearing against the bottom closure 35 of the well and extends through the tubular plunger 37 to its upper closure 39. A threaded sleeve 40 engaged with the adaptor 32 surrounds the plunger 37 and acts as a stop to prevent complete ejection of the plunger when the flared bottom end of the plunger is blocked in its movement by the bottom of sleeve 40.

A set of pressed steel vanes 41 are affixed to the upper extremity of the plunger 37 and contoured on their inner edges to permit the nesting of the bomb in the vanes when the plunger is depressed by pressure of another body in the cluster. Upon release of the bomb from a cluster, the plunger is forced outwardly by the action of the coil spring 38 so that flight stabilizing of the vanes is most effective.

For use as an incendiary, the filling 2 may have various compositions. A suitable type of incendiary oil filling is formulated by gelling gasoline or naphthahydrocarbon liquids with soaps that form stabilized gels, such as, mixtures of aluminum soaps of saturated and unsaturated fatty acids, e. g., stearates and oleates, and also such soaps with the mixtures of naphthenates and palmitates. The gelling soaps are generally used in proportions of about 7 to 15% by weight of the liquid fuel. Other suitable incendiary fillings may be formulated from liquid hydrocarbon fuels with mixtures of gelling or thickening agents, such as isobutyl methacrylate polymer, rubber, and oil thickening resins or synthetic elastomers. The gelled or thickened materials may contain dispersed finely divided complete solid materials, such as, pyrophoric materials like finely divided magnesium, cellulose nitrate, powdered carbon, woodmeal, and the like.

The bomb falling with true flight is in a substantially vertical position on striking a target, so that the force of impact is received on the head 10 of the firing pin. The fuze having been armed by ejection of the safety pin 20 when the bomb was released from a cluster dropped from aircraft, the firing pin 17 is driven by the impact into primer 21, igniting the delay train 23, which in time ignites the first fire charge 24. The ejection charge 27 is fired by the first fire charge 24 and it explosively lifts the ceiling domes 28 and 29 and forces the white phosphorus filling 30 and the incendiary filling 2 toward the tail of the bomb. The tail section 6 together with its attached stabilizing assembly is blown off and the incendiary charge is ejected from the rear of the bomb by the fired ejection charge.

In the bore 42 through the adaptor plate 5, the ejection charge 27, upon being ignited, flashes back to initiate burning of the time delay fuse 14, which after one or several seconds, depending upon the length and type of the fuse, detonates the anti-personnel charge. The fuse 14 may be timed to effect explosion of the anti-personnel fragmentation charge following ejection of the incendiary filling. The heavy anti-personnel charge deters fire fighting and allows the incendiary opportunity to act.

It has been determined that a bomb of the type described and illustrated, is useful for precision bombing of selected targets and has a much better penetrating effectiveness than other known types of incendiary bombs.

Although the invention has been described in detail with reference to one embodiment, it is to be understood that other modifications come within the spirit and scope of the invention.

We claim:

1. An incendiary bomb having a unitary nose structure comprising a hollow cap with a forward end, a base secured to said cap forming at least in part a compartment adapted to contain an explosive in the forward end of the cap and adjacent one side of the base, a primer mounted in the base, a firing pin mounted in the nose and extending through said cap so that one end

of the pin is adjacent the primer and the other end is adjacent the forward end of the cap, the arrangement being such that the firing pin detonates the primer upon impact of the forward end of the cap with an object, a fluid-tight container comprising spaced substantially cup-shaped metallic sheets secured to the opposite side of the base, said sheets forming a container for a kindling charge in the space therebetween and forming at least in part a chamber having an ejection charge adjacent said opposite side of the base, a container positioned in the chamber and having a starting charge therein, a fuse communicating with the container and the primer, another fuse having one end thereof in communication with the chamber and the other end in communication with the compartment, a hollow body portion having an incendiary substance therein, means for securing the base to the body portion so that the fluid-tight container is positioned adjacent said body portion, and a tail piece on the opposite end of said body member and mounted thereon so that pressure within said body member caused by setting off of the incendiary material by the kindling material will cause the tail piece to be released from the body.

2. A bomb having a nose structure adapted to contain an anti-personnel bursting charge, a hollow body portion secured to said nose structure and adapted to contain an incendiary charge and a tail structure secured to said body portion away from said nose structure adapted to stabilize said bomb during flight and be separated from said body portion upon ejection of said incendiary charge, said nose structure comprising a hollow cap with a forward end, a base secured to said cap forming at least in part a compartment adapted to contain an anti-personnel explosive in the forward end of said cap, a firing pin mounted in said cap extending therethrough adapted for axial movement toward said base, a primer mounted in said base adjacent said pin to flash rearwardly through said base away from said compartment upon impact with said pin, a frangible container adapted to contain a starting charge se- 45

5 cured to said base behind said primer, a first fuse in said base between said primer and said container adapted to control the time of ignition of said starting charge after ignition of said primer, a first frangible cup positioned adjacent said base on the rearward side thereof spaced apart from said container defining with said base and said container a chamber adapted to hold an ejection charge, a second frangible cup adjacent said base on the rearward side thereof concentrically surrounding said first frangible cup but spaced apart therefrom to define a kindling charge container and a second fuse extending through said base connecting said ejection charge container with said cap compartment, adapted to control the time of explosion of said nose charge after explosion of said ejection charge, whereby upon impact of said firing pin with an object, said primer, first fuse starting and ejection charges coact to separate said tail portion and eject said kindling and incendiary charges rearwardly out of said body portion, and said second fuse coacts to detonate thereafter said anti-personnel explosive in said cap.
